UNITED STATES PATENT OFFICE.

MEYER W. SCHLOSS, OF NEW YORK, N. Y., ASSIGNOR TO TREO COMPANY, INC., A CORPORATION OF NEW YORK.

MAN'S GARTER.

1,242,602.

Specification of Letters Patent. Patented Oct. 9, 1917.

Application filed January 5, 1917. Serial No. 140,659.

To all whom it may concern:

Be it known that I, MEYER W. SCHLOSS, a citizen of the United States, residing at the city of New York, in the borough of Manhattan and State of New York, have invented certain new and useful Improvements in Men's Garters, of which the following is a full, clear, and exact description.

This invention relates to men's garters and consists of certain improvements and constructions whereby durability and low cost of manufacture are achieved.

In the accompanying drawing:

Figure 1 is a front view of the improved garter; and

Fig. 2 is an end view of the front portion of the garter.

The leg-embracing strap comprises the inelastic section *a* and the two elastic sections *b*, *b*, the elastic portions being located at the front and converging downward to join at their meeting point a depending tab *c* carrying the usual button and loop for engagement with the hose. The short sections *b* of elastic webbing furnish adequate elasticity for the garter, and being located at the junction between the encircling band and the depending tab will yield to strains created by the pulling of the stocking as well as to those created by the muscle movements of the leg. In order to obtain durability of the elastic sections, it is necessary that the upper and lower edges of each section shall be of substantially the same length so that the section, as a whole, will be equally extended throughout by any strains which it is required to sustain. In order to have the upper and lower edges of the elastic sections of equal length, their extremities

must join the band *a* and the tab *c* along parallel lines. For economical reasons it is preferred to make the tab *c* of comparatively narrow tape in contradistinction to a large pad which is sometimes used at the same location, and in order to connect the extremities of the elastic sections with such a narrow tape-like tab it is necessary that the joining line or lines of stitching indicated by *d*, *d*, shall extend diagonally across the elastic webbing. Then in order to ob-

tain the equality of length between the upper and lower edges of the elastic section, its other extremity must be stitched to the end of the band *a* along a diagonal line *e* substantially parallel to the lines *d*, as illustrated. It is obvious that by using a pad at the junction of the two elastic sections, which is of sufficient area, the elastic webbing could be secured thereto by lines of stitching extending at right angles across the face of the webbing, in which case also the opposite extremity of the webbing would be secured to the band *a* by a line of stitching extending transversely to the webbing. But this could only be accomplished at the expense of a specially made pad, which expense it is desired to avoid, and is avoided, by the substitution of cheap tape-like material for the pad, which can be obtained in large quantities by the yard and merely cut up into suitable lengths to form the tab *c*. In making this tab *c*, I simply take a suitable length of tape, folded upon itself, attach the loop *f* and button *g*, respectively, to its terminals in the usual way and stitch the adjoining ends of the elastic sections to the front run of the folded tape in the manner described, leaving the rear run of tape free to swing from the bend to admit the upper edge of the hose between the two members of the folded tab.

By stitching the elastic sections along parallel diagonal lines at their respective ends, I am able to use the cheap form of tab described, and at the same time provide for uniform strain throughout the elastic sections and consequently obtain increased durability thereof.

I claim:

A garter comprising a band having elastic sections arranged at an angle to each other in combination with a tape-like tab, the extremities of each elastic section being secured to the tab and to the band, respectively, along parallel diagonal lines, substantially as described.

In witness whereof, I subscribe my signature.

MEYER W. SCHLOSS.
